W. S. MOODY

ELECTRICAL APPARATUS

Filed June 28, 1921

Inventor:
Walter S. Moody,
by *Alvy G. Davis*
His Attorney.

UNITED STATES PATENT OFFICE.

WALTER S. MOODY, OF PITTSFIELD, MASSACHUSETTS, ASSIGNOR TO GENERAL ELECTRIC COMPANY, A CORPORATION OF NEW YORK.

ELECTRICAL APPARATUS.

Application filed June 28, 1921. Serial No. 481,137.

My invention relates to electrical apparatus, and particularly to oil submerged electrical apparatus; and has for its object an improved construction and arrangement 5 of parts which is economical and readily manufactured.

In oil submerged electrical apparatus, such as transformers, some reactors, oil switches and the like, it has been found 10 that the air space above the oil in the casing which houses the apparatus has many disadvantages in addition to making the apparatus bulky and therefore needlessly expensive.

It accordingly has been proposed to eliminate the air space and fill the casing entirely 15 with oil and to take care of the expansion and contraction of the oil content thereof by the provision of an auxiliary tank or 20 casing, generally styled a "conservator" which is arranged to communicate with the main casing.

Such conservators, according to the best 25 practice, are made not only to keep the air away from the hot oil and thereby prevent sludging or rapid oxidization of the oil, but to collect and trap moisture; a special sump 30 being generally provided to this end as taught in the U. S. Letters Patent to Kulka No. 1,002,527.

It frequently becomes desirable to increase 35 the capacity of such oil submerged electrical apparatus and still maintain them as self-cooled units by suitably attaching to the casing one or more radiators or equivalent radiating units so as to decrease the normal 40 temperature rise when operating under load. These radiators must of course be in liquid communication with the oil content of the main casing at both top and bottom; otherwise there would be no circulation of 45 the oil through the radiator to dissipate the heat engendered by the electrical apparatus.

According to the practice prior to my 50 invention, these radiators were always materially shorter in length than the height of the main casing.

In tanks equipped with conservators, I 55 take advantage of the fact that the casing is entirely filled with oil in practicing my invention, since I increase the length of radiators and arrange them to communicate with the uppermost part of the cover of the casing, thereby getting a more rapid circulation of the oil and at the same time effectu-

ally increasing the radiating surface at substantially a minimum cost.

For a more complete understanding of the nature and objects of my invention reference should be had to the following detailed description when taken in connection with the accompanying drawing in which:

The figure shows in side elevation a transformer casing constructed in accordance 65 with my invention.

Referring now to the drawing, 10 denotes a casing made preferably of boiler plate for an electrical apparatus, here assumed to be a transformer, such casing being provided with a removable cover 11 with a depending outer edge portion and an auxiliary casing 12 which is in liquid communication with and serves as an expansion chamber for the oil content of the main casing. This auxiliary casing is shown as supported from the main 70 casing by means of the supporting structure 13.

Insulating bushings for the leads to the transformer windings are shown at 14 and 75 15 respectively.

Radiating units for increasing the capacity of the apparatus rated as a self cooled unit are shown at 20. Each unit comprises headers 21 at the top and bottom connected by tubular passages preferably of oval cross section. The precise construction of these 80 units is, however, no part of my present invention which resides rather in their manner of application to conservator type casings.

These units 20 have sufficient length to 85 reach from substantially the bottom of the casing 10 to the top of the cover; communication at the points in the bottom being established by means of the elbow couplings 22 leading to the bottom headers, communication with the cover 11 being established through the elbow couplings 24 extending substantially horizontally between the top 90 headers and the flanged nipples 23 which project from the depending edge portion of the cover near the uppermost part thereof.

The cost to make the radiating units 95 sufficiently long to connect with the nipples in the cover 11 over that formerly employed to connect with some point near the top of the side wall of the casing 10 is comparatively small. On the other hand this small additional cost results in a comparatively large increase in effective radiating surface.

Having now described an embodiment of 100

my invention which is at present the best means known to me for carrying the same into effect, I would have it understood that this is merely illustrative, and that I do not mean to be limited thereby to the precise details shown nor restricted in the choice of recognized equivalents except as defined in my claim hereunto annexed.

What I claim as new and desire to secure by Letters Patent of the United States, is:

A casing for electrical apparatus, said casing being provided with a removable cover having a depending outer edge portion, a plurality of radiating units spaced about

15 said casing, each of said radiating units communicating with said casing near the bottom thereof and having a connection extending from its upper end substantially horizontally to said depending edge portion of the cover near its uppermost part, said casing and radiating units being completely filled with a liquid insulating medium, and an auxiliary casing in liquid communication with and serving as an expansion chamber for said liquid insulating medium.

20 In witness whereof, I have hereunto set my hand this 23rd day of June, 1921.

25 WALTER S. MOODY.
